UNITED STATES PATENT OFFICE

121,596

DESIGN FOR A COMBINED RADIO, CLOCK, AND BOOK RACK

Stephen D. Nicholas, Arcadia, Calif.

Application December 23, 1938, Serial No. 81,958

Term of patent 3½ years

To whom it may concern:

Be it known that I, Stephen D. Nicholas, a citizen of the United States residing at Arcadia, in the county of Los Angeles and State of California, have invented a new, original, and ornamental Design for Combined Radio, Clock, and Book Rack, of which the following is a specification, reference being had to the accompanying drawing, forming a part thereof, and in which:

Fig. 1 is a perspective view of a combined radio, clock and book rack showing my new design.

Fig. 2 is a rear elevational view thereof.

In the two figures the design of the right hand end portion has been omitted, as it is the same as that shown on the left hand illustration in Fig. 1.

I claim:

The ornamental design for a combined radio, clock, and book rack, substantially as shown and described.

STEPHEN D. NICHOLAS.
